M. E. HOSTATER

DISHWASHING MACHINE

Filed Feb. 5, 1921

Patented Feb. 17, 1925.

1,526,985

UNITED STATES PATENT OFFICE.

MARGARET E. HOSTATER, OF BUFFALO, NEW YORK.

DISHWASHING MACHINE.

Application filed February 5, 1921. Serial No. 442,859.

To all whom it may concern:

Be it known that I, MARGARET E. HOSTATER, a citizen of the United States, residing at Buffalo, in the county of Erie and State of New York, have invented certain new and useful Improvements in Dishwashing Machines, of which the following is a specification.

This invention relates to dish washing machines and particularly to that type wherein the dishes are disposed in a perforate receptacle rotatably mounted in a container partially filled with cleansing fluid such as hot water and soap.

The principal object of the invention is to mechanically effect the cleansing of dishes or other objects by revolving them against the inertia of a cleansing fluid in such a manner that the possibility of breaking the dishes will be eliminated and the hands of the operator will not at any time come into contact with the cleansing fluid.

Another object of the invention is to improve upon the dish washing machines now in use by reducing the number of parts necessary to accomplish the result and by so constructing those parts remaining that accumulation of sediment will be prevented and cleaning of the machine will be greatly facilitated.

Other objects will be in part obvious and in part pointed out hereinafter.

The invention consists, furthermore, in the novel arrangement and combination of parts hereinafter described, as well as in the details of the construction of the same, all of which will be more fully described in the following specification, and then finally embodied in the claims which are appended to this specification and which form an essential part thereof.

In the drawings:—

Figure 1 is a sectional side elevation of the operative assembly.

Figure 2 is a plan view of the base partly in section, with the operating mechanism removed.

Figure 3 is a detail view of a portion of the stuffing box.

Figure 4 is an inverted plan view of the perforated receptacle illustrating the reinforcing bars for the bottom of the receptacle.

Like characters of reference refer to like or corresponding parts throughout both views, in the drawings.

In general terms the invention consists in a container A mounted on a base B and having rotatably mounted therein a perforate receptacle C actuated by a driving element D connected with a suitable source of power (not shown) such as an electric motor or provided with a crank handle (not shown) for manual operation as is the case with the embodiment hereinafter illustrated and described in detail.

The container A is formed of a body portion 1, the lower edge of which is bent inwardly substantially at right angles thereto to form an annular flange 2 to which the bottom 3 is secured by means of bolts 4 extending through the base B and serving also to hold the container thereupon. Formed concentrically of the bottom 3 is an opening 5 the edges of which are secured to the base B as at 6, for receiving the drive shaft of a drive element (hereinafter described) suitable packing being provided to prevent leakage from the container therabout. Another opening 7 communicating with a conduit (not shown) serves as a drain for carrying off the cleansing fluid subsequent to use of the machine. The upper edge of the side wall 1 is beaded as at 8 for supporting a cover 9 having secured on the under portion of its peripheral edge an annular L-shaped ring 10 for engaging about the bead as is illustrated. Riveted as at 11 to the nether face of the cover 9 and in line with the opening 5 is a stub bearing 12 the purpose of which will be hereinafter described. Suitable handles 13 are provided for facilitating removal of the cover.

The base B is provided with a plate top portion 14 secured to the container as at 4 and is preferably cut away as at 15 in the quadrants to decrease the weight thereof, the peripheral edges thereof being flanged as at 16 and 17 for receiving the container A and for receiving the supporting legs 18 respectively; the upper ends of said legs 18 being bent as at 19 to engage the inner surface and lie flush with the outer surface as is shown in Figure 1. Bolts 20 are provided for securing the legs to the flange 17 and the lower ends of the legs are likewise bent as at 21 for attachment by bolts 22 to the flange 23 formed on the bottom portion 24 of the base. Furthermore the bottom portion is provided with foot flanges 25 and is cut away in quad-

- rants as at 26 to lighten the frame. Suitable securing means (not shown) may be inserted through openings 27 in the flanges 25 for mounting the machine upon a stand.
- 5 Aligned openings 28 and 29 formed concentrically in the top and bottom portions of the base are adapted to receive bearings for the drive element hereinafter described, and an extension 30 on the web portion of the 10 bottom between two of the cut away portions 26 is provided with an opening 31 for mounting a crank shaft, another portion of which is journaled through one of the legs 18 as at 32.
- 15 The plate 14, centrally thereof is formed with an opening 14', and surrounding the opening 14', and arranged in the upper face of the plate 14, is a pocket 15', in which is positioned an apertured disk 16', the opening in the latter registering with the opening 14'. The bottom 3 of the container is provided with a centrally disposed opening 5, and across said opening extends the disk 16'. Hold fast devices 6 are employed for 20 connecting the bottom 3 to the plate 14, as well as connecting the disk 16' therewith. Extending through the opening 14', as well as into the aperture of the disk 16', and furthermore depending from the plate 14, is a 25 bearing sleeve 17', formed with an annular flange 18', and further having its lower portion peripherally threaded. The bearing sleeve 17', is secured with the plate 14, through the medium of the hold fast devices 6, engaging the flange 18'. Interposed 30 between the flange 18' and the plate 14, is an apertured disk Y.
- The disk 16' is formed of asbestos, and the disk Y made of rubber. The disks are 40 employed to prevent leakage of the cleansing fluid. Threadably engaging with the bearing sleeve 17', is a lock nut 62, carrying a packing 19'. A spring 62' is employed and which engages in the nut 62, to arrest 45 rotative movement thereof. The nut 62 is formed with peripheral grooves 63, for the reception of the spring 62', the latter is secured to and depends from the plate 14.
- 50 A receptacle C for containing the plates or dishes to be washed is provided with a side wall 33 and a bottom 34 perforated as at 35 and said bottom being flanged as at 36 for securement to the side wall 33 by bolts or rivets 37 carried by transverse reinforcing bars 38, the medial portion of which is depressed as at 39 and provided with a squared opening 40 for receiving the drive shaft of the drive element D. As the receptacle C is revolved through connection 55 of the drive element D, with the medial portion of the transverse bars 38 they are secured throughout their length to the bottom by spaced rivets 41. Adjacent the upper edge of the side wall 33 is an overflow opening 42 reinforced by a plate or casting 60 65 70 75 80 85 90 95 100 105 110 115 120 125 130
- 43 suitably secured as at 44 thereabout. The upper edge of the wall 33 is beaded as at 45 for supporting a cover 46 to which is secured on its under side adjacent the peripheral edge thereof an annular L-shaped ring 47 for engaging about the bead as is illustrated. Handles 48 are mounted in the bent portion of the wall forming the bead 45. The handles 48 are extended upwardly through recesses formed in the ring 47 and cover 46 to prevent independent rotation of the cover with respect to the body of the receptacle, and said handles 48 also provide means for lifting the receptacle C and its cover 46 together. Mounted concentric of the cover and in alignment with the stub bearing 12 and squared opening 40 is a pintle 49 journaled in the stub bearing 12 for an obvious purpose. Suitable handles 50 are provided for removing the cover independently of the body portion of the receptacle C.
- The drive element D includes a transverse crank shaft 51 mounted in the extension 3 and opening 32 in one of the legs 18 of the base B and has thrust collars 52 secured thereon for preventing longitudinal movement thereof. A vertical drive shaft 53 has its lower end anti-frictionally mounted in the stub bearing 54 provided with a ball-race 55 for receiving the ball bearings 56 and is provided with a bevel gear 59 intergeared with a master gear 60 on the crank shaft for rotating the drive shaft. A suitable closure plate 57 is bolted therebeneath for an obvious purpose. The opposite end of the drive shaft is squared as at 61 for reception within the squared opening 40 in the transverse bars 34 of the bottom of the receptacle C; the under portion of the bars adjacent the squared opening abutting the upper portion of the sleeve 58 for supporting the receptacle in spaced relationship to the container A.
- The terminal of the crank shaft 51 is squared as at 64 for receiving either a crank handle (not shown) or for connection with a suitable power plant such as a motor (not shown).
- In operation the container A is partially filled with a cleansing fluid such as soap and water and the dishes are placed in the receptacle C, whereupon the crank shaft 51 of the drive element D is rotated consequently rotating the receptacle C through the drive shaft 53 causing the cleansing fluid (on account of its inertia) to pass rapidly over and between the dishes removing the particles of food or other matter. The container is then drained through the opening 7 and clean hot water placed therein and the operation repeated.
- Many changes may be made in the construction of the device as a whole, and in the several parts as well as in their combination.

tions and many rearrangements of the several parts may be had without in any way departing from the field and scope of the present invention as disclosed by this application, wherein only the preferred form of the same has been shown and described.

What I claim and desire to secure by Letters Patent is:

1. In a washing machine a rotatable foraminous receptacle having driven means connected with its bottom for rotating it, a bearing arranged above said receptacle, a removable cover for said receptacle provided with a bearing element extending into said bearing, and a lifting means carried by the body of the receptacle and extending through the cover to provide for the bodily
- 10 rotation of the latter with said body portion.
2. In a washing machine a rotatable foraminous receptacle having driven means connected with its bottom for rotating it, a bearing arranged above said receptacle, a removable cover for said receptacle provided centrally with a bearing element extending into said bearing, lifting means carried by the body portion of the receptacle and extending through the cover to provide for the bodily rotation of the latter with said body portion, and means for lifting the cover independently of the lifting means for the body of the receptacle.
- 15
- 20
- 25
- 30

In testimony whereof, I affix my signature hereto.

MARGARET E. HOSTATER.
